UNITED STATES PATENT OFFICE

2,448,310

CLOTHESLINE

Ernest C. Hansen, New Orleans, La.

Application December 13, 1946, Serial No. 716,095

7 Claims. (Cl. 211—119.15)

1

This invention relates to a clothes line apparatus.

An object of this invention is the construction of a simple and efficient clothes line apparatus that eliminates props or poles that are usually employed for partly supporting the clothes line while clothes are being dried.

Another object of the invention is the construction of an apparatus in which several clothes lines are employed and which lines can be easily raised or lowered by means of a manually operated winch.

A still further object of the invention is the construction of a simple and efficient apparatus in which there is a floating clothes line structure, which also involves means for substantially keeping a plurality of lines balanced and which clothes line structure may be easily lowered by manually operated means for placing clothes upon the clothes line, and equally as easy is the clothes line structure raised to its drying position.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Figure 1 is a view in side elevation of a clothes line apparatus constructed in accordance with this invention, while

Figure 2 is a top plan view of the same.

Figure 3 is a view in elevation of the left hand end of the apparatus.

Figure 4 is a sectional view taken on line 4—4, Figure 2, and looking in the direction of the arrows.

Referring to the drawings in which the preferred embodiment of this invention is illustrated, 1 designates the primary standard and 2 the auxiliary standard. These standards 1 and 2 are preferably formed from suitable pipes and may be of any length that the operator desires.

On the primary standard 1 is a winch 3 which is provided with the usual drum 4. Drum 4 is provided with a worm gear 5 (Fig. 3) which meshes with the worm gear 6; worm gear 6 is operated by a crank 7. Two cables 8 are suitably attached to the drum 4 whereby the cables may be wound and unwound as the operator desires by manipulating crank 7.

On the upper end of primary standard 1 is a pipe-like horizontal primary bar 9. On the ends of the primary bar 9 are caps 10 which carry

2

fixed rest arms 11. These rest arms 11 extend slightly downwardly for the purpose hereinafter described. On the lower or outer end of each rest arm 11 is a cap 12, and cap 12 is provided with an upwardly extending stop 13. A floating pipe-like bar 14 is placed across the rest arms 11 and the upper or outer end of cables 8 are connected to said floating bar 14, Fig. 2. Cables 8 are mounted upon the upper sheaves or pulleys 15 and these cables pass through sheave device 16 that is carried by the primary standard 1.

On the ends of floating bar 14 are caps 17, each cap provided with a depending inwardly extending balance hook 18.

The auxiliary standard 2 is provided with a pipe-like horizontal auxiliary bar 19 which is supported at its middle upon the top of said auxiliary standard 2. Preferably three eye bolts 20 are mounted upon the auxiliary bar 19 and pivotally mounted on each bolt is a swinging arm 21. The steel clothes lines 22 are each supported at one end upon a swinging arm 21 and its other end is attached to an eye bolt 23 carried by the floating bar 14.

When the clothes are to be placed upon the clothes lines 22 the structure is as shown in Figure 1, with the floating bar 14 resting upon the rest arms 11. The floating bar 14 cannot slide off said rest arms 11 even though the cables 8 are very slack because the stops 13 will prevent such displacement. When it is desired to lift the clothes lines 22 to the dotted position shown in Figure 1, the operator rotates the crank 7 to cause cables 8 to be wound upon drum 4. The

balancing hooks 18 will prevent too much sagging of the clothes line structure at one side of the apparatus, whereby the clothes lines 22 are retained normally in a substantially horizontal position even though one side of the clothes lines 22 may contain considerable more clothes or weight than the other side.

A hook arm 24 extends from the plate 25 of the winch 3, Fig. 1. This hook arm is useful in supporting clothes pin container, garden hose, or the like.

The sheave device 16 is provided with two sheaves or pulleys 26, Fig. 3, over which the cables 8 pass to the upper or large sheaves or pulleys 15.

It is to be understood that the balancing hooks 18 engage the under face of the rest arms 11 and slide along said arms if necessary, as the floating arm 14 is raised by the cables and winch 3 when the clothes lines 22 are raised to their up-

per position, as when the apparatus is loaded with the clothes to be dried.

A single person can operate this efficient apparatus both in loading the clothes on the clothes line as well as operating the winch. The apparatus affords excellent means for drying the clothes, as well as handling the same for placement or for removal after drying.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such alterations or changes as shall fairly fall within the scope of the appended claims.

What I claim is:

1. In a clothes line apparatus, the combination of a primary and an auxiliary standard, rest arms and means supporting said rest arms upon said primary standard, a floating bar above said rest arms, clothes lines attached to said floating bar, means movably fastening said clothes lines to said auxiliary standard, and means for raising and lowering said floating bar.

2. In a clothes line apparatus, the combination of a primary and an auxiliary standard, rest arms and means connecting said rest arms to said primary standard, said rest arms provided with stops, a floating bar above said rest arms and capable of engaging said stops, clothes lines attached to said floating bar, means movably connecting said clothes lines to said auxiliary standard, a winch mounted on said primary standard, and cables extending from said winch and connected to said floating bar.

3. In a clothes line apparatus, the combination of a primary and an auxiliary standard, said primary standard provided at its upper end with a horizontal primary bar, caps on the outer ends of said primary bar, depending rest arms mounted at their inner ends upon said caps, each rest arm provided on its outer end with a cap, said last mentioned cap provided with an upstanding stop, a floating bar above said rest arms, sheaves on said horizontal primary bar, a winch carried by said primary standard, cables extending from said winch and over said sheaves and fastened to said floating bar, clothes lines fastened at one end to said floating bar, and means fastening said clothes line to said auxiliary standard.

4. In a clothes line apparatus, the combination of a primary and an auxiliary standard, said primary standard provided with a primary bar, said primary bar provided with rest arms,

a floating bar above said rest arms, said floating bar provided with balancing hooks adapted to engage said rest arms, a clothes line attached to said floating bar, means for attaching said clothes line to said auxiliary standard, and manually operated means on said primary standard and primary bar and connected to said floating bar for operating said floating bar.

5. In a clothes line apparatus, the combination of a primary and an auxiliary standard, said primary standard provided at its upper end with a horizontal bar, said horizontal bar provided with rest arms, a floating bar above said rest arms, said floating bar provided on its ends with hook-carrying caps, said hooks extending inwardly under said rest arms, a clothes line attached to said floating bar, means movably connecting said clothes line to said auxiliary standard, and means for raising and lowering said floating bar with respect to said rest arms.

6. In a clothes line apparatus, the combination of a primary and an auxiliary standard, a movable clothes line structure on said standards, and said clothes line structure provided with balancing hooks, said primary standard provided with means engaged by said balancing hooks, and manually operated means connected to said clothes line structure for raising and lowering the same.

7. In a clothes line apparatus, the combination of a pair of standards, a clothes line structure including a floating bar and swinging arms, means connecting said swinging arms to one of said standards, means on the other standard for supporting said floating bar, manually operated means on said last mentioned standard and connected to said floating bar for operating said floating bar, and said floating bar provided with balancing means engaging means on said last mentioned standard for keeping said clothes line structure in a relatively horizontal position.

ERNEST C. HANSEN.
